UNITED STATES PATENT OFFICE.

THEODORE B. OSBORNE, OF PLAINFIELD, NEW JERSEY, ASSIGNOR TO ALFRED OSTERHOUDT, OF BROOKLYN, NEW YORK, ROBERT J. ARMOUR, OF ORANGE, NEW JERSEY, AND LAWSON C. HUNTINGTON, OF NEW YORK, N. Y.

SWITCH-LAMP.

SPECIFICATION forming part of Letters Patent No. 335,951, dated February 9, 1886.

Application filed June 15, 1885. Serial No. 168,807. (No model.)

To all whom it may concern:

Be it known that I, THEODORE B. OSBORNE, a citizen of the United States, and a resident of Plainfield, in the county of Union and State 5 of New Jersey, have invented certain new and useful Improvements in Switch - Lamps, of which the following is a specification.

My invention relates especially to lamps or lanterns employed at railway-switches, &c., 10 and has for its object the provision of a cheap, simple, durable, and effective device to prevent the extinguishing of the light by reason of sudden jars caused by the passing of trains over the switch wherewith the lantern is used.

15 The invention consists, essentially, in a spring interposed between the socket-plate fitting upon the switch-staff and the body of the lantern, suitable means being employed to permit the vertical movement of the body, 20 all of which will be hereinafter first fully described, and then pointed out in the claim.

In the drawings, Figure 1 is a view in elevation of a switch or signal lantern wherein 25 my improvement is employed, the bottom part thereof being shown in section; and Fig. 2 is an enlarged view of a fragment of the base of the device, illustrating the method employed for securing the parts together while permitting a vertical movement of the body of the 30 lantern upon the socket-plate.

Like letters of reference wherever they occur indicate corresponding parts in both the figures.

A is the body of the lantern, provided with 35 a hollow base or skirt, B. C is a socket-plate, preferably made of cast metal, said plate having slots C' therein, through which rivets or

projections D, secured to or formed upon the skirt or base, extend. E is a spring interposed between the lantern - body and the socket-plate. 40

When constructed and arranged in accordance with the foregoing description, and placed in position upon a switch-staff, it will at once be seen that while the socket-plate fits rigidly 45 upon the staff the spring thereabove will prevent a sudden jar of the lamp, and sufficient play in a vertical direction is given to the lantern-body to permit free operation of the spring. 50

I am acquainted with Letters Patent No. 55,255, issued to Dodge June 5, 1866, for an improvement in car - lamps, and with No. 319,094, issued to Huntington June 2, 1885, for an improvement in switch or signal lamps, 55 and to the constructions therein shown and described make no claim; but,

Having now fully described my invention, what I claim as new therein, and desire to secure by Letters Patent, is-- 60

The combination, with the socket-plate C, having the outer depending flange provided with slots C' therein, of the body A, having skirt or base B, provided with projections D, and the spring E, the whole combined and arranged substantially as shown and described. 65

Signed at New York, in the county of New York and State of New York, this 6th day of June, A. D. 1885.

THEODORE B. OSBORNE.
